(57) CLAIM

The ornamental design for a playing surface for a game, as shown and described.

DESCRIPTION

FIG. 1 is a front top perspective view of an ornamental design of a first exemplary embodiment of a playing surface for a game showing my new design;

FIG. 2 is a top view thereof;

FIG. 3 is a front view, a rear view being a mirror image thereof;

FIG. 4 is a side view in a direction rotated 45 degrees from the view of FIG. 3, an opposite side view being a mirror image thereof;

FIG. 5 is a front top perspective view of an ornamental design of a second exemplary embodiment of a playing surface for a game showing my new design;

FIG. 6 is a top view thereof;

FIG. 7 is a front view, a rear view being the mirror image thereof; and,

FIG. 8 is a left side view, a right side view being the mirror image thereof.
